UNITED STATES PATENT OFFICE.

ANIELLO DE VIVO, OF BAYONNE, NEW JERSEY.

SHARPENING OR HONING MACHINE.

Application filed October 5, 1922. Serial No. 592,576.

The present invention relates to machines or devices for sharpening and honing, and more particularly for sharpening and honing razors, the machine or device being of the same type generally as that described and shown in my Patent No. 977,172, dated Nov. 29, 1910, the device described in said patent however, being of relatively small dimensions for easy portability, as in the pocket of the user, while the present machine or device although compact and portable is of larger dimensions and sturdier construction than the first device, and better adapted to sustain the wear and strain incident to use where razors in large numbers are to be operated upon, as in the case of a business concern which sharpens and hones large numbers of razors, or where the machine or device is used by a person who travels about from place to place and operates upon a large number of razors in the course of his travels.

One object of the invention is to provide a machine for sharpening or grinding razors which comprises means for honing the razors as well.

Another object is to provide a machine by which a razor may be sharpened or ground, while a second razor may be honed concurrently with the sharpening or grinding of the first mentioned razor.

Another object is to provide a machine constructed and arranged to sharpen or grind automatically the blade of a razor uniformly and evenly throughout its length.

Another object is to provide a machine for honing automatically the blade of a razor.

Another object is to provide a machine by which a razor may be automatically sharpened or ground, while a second razor may be automatically honed concurrently with the sharpening or grinding of the first mentioned razor.

Another object is to provide a machine of the character mentioned which is operated by electricity.

Another object is to provide a machine of the character mentioned having a carriage for razor blade holding or clamping means, this carriage being reciprocatable transversely to the sharpening or grinding means of the machine, and the machine having razor blade honing means rotatable in reverse directions, the rotation of which in reverse direction is substantially synchronous with

the reverse movement of said carriage when the carriage is reciprocated.

To the accomplishment of the above objects, and such other objects as may be disclosed in the course of the subjoined description by way of example of one embodiment of the invention shown in the accompanying drawings in which Figure 1 is a plan view of the machine arranged in an enclosing box or case.

Figure 2 is a side elevation on the line 2—2 of Fig. 1, looking in the direction of the arrow, one side of the enclosing box or case being removed.

Figure 3 is a bottom view, or view of the under side of the machine.

Figure 4 is a detail bottom view, or view of the underside, on an enlarged scale, of the carriage and razor blade holder or clamping means.

Figure 5 is a detail sectional side view, on an enlarged scale, of the clamping portions of the razor blade holder and carriage.

Figure 6 is a fragmentary detail plan view of the honing mechanism on an enlarged scale.

Figure 7 is a side elevation of Fig. 6, partly in section on the same scale as Fig. 6 and

Figure 8 is an end elevation looking in the direction of the arrow of Fig. 6, and on the same scale as Fig. 6.

Similar reference characters denote similar parts throughout the several views.

The invention, as shown, comprises, the posts or supports 10, having at their lower ends suitable bases secured to the foundation plate 11 which in the present instance is secured to an enclosing box or case. The table or platform 12 is secured to the upper end of the posts or supports 10, to which table or platform the supporting plate 13 is secured, the supporting plate having a raised upper surface portion 14.

The motor 15 rests upon the foundation plate 11 and is operatively connected to the drive wheel 16 fixed on the drive shaft 17 turning in bearings 18 and 19 secured to the upper side of the supporting plate 13, one end of the drive shaft being extended beyond the edge of the plate 13, and having fixed on its extended end the small gear 20 which meshes with the large gear wheel 21 fixed on the short or stub shaft 22 arranged parallel to the drive shaft and turning in a bearing, not seen, secured to the supporting

plate 13, the speed of rotation of the stub shaft being reduced.

The stub shaft 22 extends beyond the edge of the supporting plate 13 and has on its extended end the intermediate sprocket 23 and the outer sprocket 24, the sprocket 23 being connected by the sprocket chain 25 to the sprocket wheel 26 fixed on the shaft 27, Fig. 3, later mentioned. The sprocket 24 is connected by the sprocket chain 28 to the sprocket wheel 29 fixed on one end of the worm shaft later mentioned.

The grinding wheel 30 is mounted on the drive shaft 17, being located in a position about midway of the length of the supporting plate 13.

The slideable rod 31 is supported in raised bearings 32 and 33 secured to the upper side of the raised surface portion 14 of the supporting plate, and has secured thereto the cross-piece or cross-block 34 which is slideable with the rod 31 and prevents rotation of the rod 31 during its sliding movement.

The rod 31 is provided on its upper side near its opposite ends with the substantially horizontally projecting pins 35 and 36, each of which extends slightly over the worm shaft later described, and is provided near one of its ends, the inner, on its under side, with the downwardly projecting pins 37 and 38, oppositely disposed to and adjacent to each other and extending below the supporting plate 13 and table or platform 12, through registering openings in said plate and table, the purpose of the pins 35 and 36, and 37 and 38, being later stated.

The worm shaft 39 is supported by the bearings 40 and 41, these bearings being secured to the under side of the supporting plate 13, which plate, and the table or platform 12 as well, has therein the opening 42 through which a portion of the upper side of the worm-shaft, particularly the worm thereof, is exposed for the purpose later stated. The worm shaft has thereon stop collars 43 and 44 for preventing longitudinal movement of the worm shaft. One end, 45, of the worm shaft is extended, on which the sprocket 29 is mounted.

The worm-shaft 39 is provided with the worm 46 having the worm-groove 47, the worm-groove having at its respective ends the inclined faces 48 and 49, Fig. 3, for the purpose later stated.

The slide-plate or strip 50, is arranged parallel and adjacent to the opening 42, one edge of the slide-plate or strip extending slightly over said opening, this plate or strip being raised above or spaced above the supporting plate 13 by the posts or supports 51 and fastened to these posts or supports which are secured at their lower ends to the supporting plate.

The carriage for the razor blade holder

comprises the up-standing side-pieces 52 and 53 and the base-block 54. Each of the side-pieces 52 and 53 is cut away or recessed in its under or bottom side in the mid-portion of the side-piece, shown by the dotted lines 70 of Figs. 1 and 4, to permit the side-pieces to engage transversely and slidably the slide-plate or strip 50, the side-pieces being retained in this sliding engagement by the projecting ends of the plates 55, 56, 57 75 and 58 secured to the under sides or edges of the side-pieces and extending over the under side of the slide-plate or strip. The base-block 54 is secured between the side-pieces 52 and 53, and has longitudinally 80 thereof in its upper surface a recess or slide-way, in the present instance of dovetail shape in cross-section, in which the supporting base-member, later described, of the razor blade holder is received.

The razor blade holder comprises the supporting base member 59, the T-shaped end-piece 60 and the tilting arm 61.

The supporting base member 59 is conformably engageable in the recess or slide-way of the base block 54 and has on its upper surface the up-standing side-pieces or bearing-pieces 62 and 63.

The T-shaped end-piece 60 comprises the short stem or leg portion 64, and the long cross-piece or head portion which constitutes the inner clamping member 65 of the holder. The stem or leg portion 64 is received between the side-pieces or bearing-pieces 62 and 63 of the base member 59 and is provided with laterally extending arms or pins passing through these side-pieces or bearing-pieces whereby locking or tilting movement of the leg-portion, and the head portion as well, is afforded. The head portion or clamping member 65 has near the ends thereof and extending therethrough adjustable bolts 66 and 67, these bolts being provided with adjusting nuts 68 and 69, the outer ends of these bolts being secured in 100 and carrying the outer clamping member 70, the outer clamping member being movable away from or towards the inner clamping member by adjustment of the nuts 68 and 69, the outer clamping member being supported midway of its length by the guide member 71, Fig. 4, attached to the outer clamping member and sliding in a bore, not shown, in the inner clamping member.

The outer clamping member 70, Fig. 5, has on the inner edge thereof, longitudinally of the outer clamping member and extending towards the inner clamping member, a flange or rib 72 for co-operating with the adjustable screws 73 and 74, extending through the inner clamping member, to hold the blade of the razor between said flange and screws.

The tilting arm 61, is secured at one end to the stem or leg portion 64 of the T-

shaped end-piece between the side-pieces 62 and 63 of the base member 59 of the razor blade holder, and is provided at its outer or free end with an open ended slot 75 in which the adjusting pin 76 engages. The adjusting pin 76 is secured at its lower end to the base member 59 and is provided at its upper end with an adjusting nut 77 which bears on a collar or annular extension 78, 10 loosely mounted on the pin 76, the helix spring 79 being arranged around the pin 74 between the under side of said collar or extension 78 and the upper side of the base member 59, for yieldably maintaining or 15 supporting the outer end of the tilting arm. It will be noted that the T-shaped end-piece, and with it the inner and outer clamping members, may be slidably moved on the base member 59 towards or away from the 20 grinding wheel, and held in desired position by the adjustable screw 59', and that by compression of the spring 79 by means of the adjusting nut 77, the T-shaped end-piece, and with it the inner and outer clamping 25 members, may be tilted upwardly, and that by release of the compression of the spring 79 by means of the nut 77, said end-piece and clamping members as well may be tilted downwardly, the effect being that by the 30 adjustment of said nut, the razor blade when clamped or held between the inner and outer clamping members, may be adjusted relative to the grinding wheel 30, and any desired curvature may be given to the blade 35 in grinding or sharpening.

The base block 54, Fig. 5 has an extension or plate 80 which extends downwardly to a position adjacent to the under side of the carriage of the razor blade holder for supporting the carrying member 81 for the cross-over dog 82, to permit engagement of the cross-over dog in the worm-groove 47 of the worm-shaft for providing reciprocatable movement of the razor blade carriage 45 and holder by rotation of the worm-shaft, whereby the razor blade is carried by reverse movement transversely across the face of the grinding wheel. The cross-over dog 82 is pivotally attached to the carrying member 81 between raised side-portions 83 and 50 84 thereof, Fig. 4, whereby the pivotal or rotative movement of the cross-over dog is limited.

As relating to the razor honing feature of 55 the invention: The shaft 27, Fig. 3, which turns in bearings secured to the under side of the table or platform 12, and on which shaft the sprocket wheel 26 is mounted, is provided on its mid length with the sleeve 85, 60 loose thereon. The sleeve 85 has at its inner end the bevel gear 86 having the clutch member 87 attached thereto, and has at its outer end the bevel gear 88 having the clutch member 89 attached thereto. The shaft 27 65 adjacent to the clutch member 87 is pro-

vided with the clutch member 90, having the groove 91 and collar 92, splined on the shaft 27 against rotation except with the shaft and slideable for a short distance thereon, the clutch member 90 being engageable 70 with and disengageable from the clutch member 87 by sliding movement on said shaft. The shaft 27 adjacent to the clutch member 89 is provided with the clutch member 93, having the groove 94 and collar 95, 75 splined on the shaft 27 against rotation except with the shaft and slideable for a short distance thereon, the clutch member 93 being engageable with and disengageable from the clutch member 89 by sliding movement on 80 the shaft 27. The large bevel gear 96 is mounted on the shaft 97 on the under side of the table or platform 12 in position to mesh with the bevel gears 86 and 88. The shaft 97 is supported by suitable bearings, 85 not seen, and extends upwardly through the table or platform 12 and supporting plate 13 to a position above the plane of the drive-shaft 17.

For shifting the clutch members 90 and 93 the shift plates or shifters 98 and 99 rigidly connected to each other by the rod or bar 100 are arranged to engage in the grooves 91 and 94 of the respective clutch members 90 and 93. The connecting rod or 95 bar 100 has rigidly secured thereto and spaced therefrom the yoke or bail 101 having in its mid length the longitudinal slot 102, Figs. 2 and 3, the purpose of said yoke or 100 bail and slot being later stated.

The shifting arm 103 is pivotally secured about midway of its length to the under side of the table or platform 12 and parallel to the horizontal plane of said table. The arm 103 is preferably of the shape shown in 105 Fig. 3, having a body 104, and a neck 105, the end of this neck, when the arm is in normal operative position, lying obliquely between the downwardly projecting pins 37 and 38 of the slideable rod 31 being held in 110 this position by the spring later mentioned. The arm 103 is provided at the outer end of its body 104 with aligned spaced pins 106 and 107 which extend downwardly. One end of the shifting lever 108 is engaged 115 obliquely, or bound by contact, between the pins 106 and 107, and the opposite end or point 109 of said lever is engaged in and extends through the before mentioned slot 102 of the yoke or bail 101, being as shown 120 in Fig. 3 engaged in the outer end of said slot.

The spring 110 is attached at one of its ends to the extreme end of the neck 105 of the shifting arm, and is attached at its opposite end to the shifting lever near the end or point 109 thereof, the tendency of this spring being to pull the end or point 109 towards the neck 105, whereby the point 109 as shown is maintained in the outer end of 130

the slot 102 and the neck of the arm 103 is maintained in position between the pins 37 and 38, and the clutch member 89 in consequence is maintained in engagement with the clutch member 87, and the large bevel gear 96, and with it the shaft 97, will be caused to rotate in one direction, that shown by the upper arrow of Fig. 3.

It will be noted that if the arm 103 and shifting lever 108 be caused to shift to the positions shown in outline in Fig. 3, the clutch member 89 will be thrown out of engagement with the clutch member 87, and the clutch member 93 will be thrown into engagement with the clutch member 89, with the result that the bevel gear 96, and with it the shaft 97, will be caused to rotate in direction opposite to its former rotation, or in direction of the lower arrow of Fig. 3.

Referring to Fig. 7, the raised surface 14 of the supporting plate 13 has thereon the bored boss 112 through which the shaft 97 passes. The small gear wheel 113 is arranged on the shaft 97 on the upper end of the boss 112, being retained in position by the stop collar 114 and turning with the shaft 97. The shaft 97 has thereon above the collar 114 the supporting disk 115 secured to the shaft 97 by the set screw 116 and turning with the shaft. The honing disk 117 is arranged on the supporting disk 115 to rotate with the shaft 97, being removably retained in position by the thumb nut 118. The raised surface 14 has thereon the boss or support 119 upon which is loosely mounted the gear wheel 120, which meshes with the small gear wheel 113. The gear wheel 120 has in its upper surface the series of holes 121, the arm 122 being removably secured at one end by the screw 123 to the gear wheel 120 engaging in a desired one of these holes, the holes 121 and screw 123 permitting regulation of the length of the stroke of the arm 122. The arm 122 at its opposite end is attached to the straight stem portion 124 of the slidable block 125 arranged for slidable movement longitudinally of the rod 126 which is seated at one end in the cross plate 127 extending between the supports 128 and is seated at its other end in the cross plate 129 extending between the supports 130. The slidable block 125 is provided with the forked stem piece 131, the forked end of which engages in the groove 132 of an extended portion of the razor heel clamp 133. The razor heel clamp 133 is provided on one side with the longitudinal recessed portion 134, the set screws 135 and 136 passing through the heel clamp into the recessed portion 134 and being engageable with the heel of the razor for retaining the razor in the heel clamp. The heel clamp on its side opposite to the recessed portion 134 has a raised longitudinal portion or slide

face, not seen, which engages in the slide-way 137 of the shaft 138 for permitting sliding movement of the heel clamp on this shaft and also affording rotative movement of the heel clamp with the shaft 138. The shaft 138 is journalled at its inner end in the cross plate 127 and at its outer end is extended and passes through the cross plate 129, being at this end provided inwardly of the cross plate 129 with the stop collar 139 and outwardly of the cross plate 129 with the spacing bearing 140, the small gear wheel 141 being fixed on the outer end of the shaft 138 and turning with this shaft.

The slidable rod 31, Fig. 1, has thereon the horizontally extending pin 142 with which one of the forked ends 143 of the arm 144 engages. The arm 144, Fig. 6, is of bell-crank shape and is pivoted at its angle, as at 145, to an extension 146 of the plate 14. The other forked end 147 of the arm 144 engages the stem 148 of the gear segment 149 which is pivotally secured by the stud 150 to the cross plate 129, and is provided with the teeth 151 engaging the small gear wheel 141. The gear segment 149 has on its converging sides plungers, 152-153, the plunger 152 being engageable in the dash-pot 154 and the plunger 153 being engageable in the dash-pot 155, the dash-pots being secured at their bases to the plate 14 of the foundation, and each having a hole such as 156 for escape of air. The helix spring 157 is secured at one end to the pin 158 located near the upper edge of the gear segment and is secured at its lower end to an extension such as 159 located below the edge of the table 12, the purpose of the spring 157 being to prevent the gear segment from becoming caught or fixed on its pivotal center.

It will be noted that upon pivotal movement of the arm 144, the gear segment 149 will be given a rocking motion whereby a partial rotary, or side to side, motion will be imparted to the shaft 137 and razor heel clamp 133.

For sharpening shears, scissors and the like, a suitable grinding wheel, not shown, may be substituted for the disk 117, the rest 160, which is pivotally movable and adjustably positionable as shown in outline, being provided for maintaining the cutting edge of the shears, not shown, in sharpening contact with the substituted grinding wheel by manually holding the back edge of the shears in contact with the raised flange 161 of the rest. In operation:

The blade of the razor being clamped between the outer and inner clamping members 65 and 70 of the razor blade holder and suitably adjusted relative to the grinding wheel 30, the motor 15 and drive wheel 16 are set in motion by operation of a suitable switch S connected to a source of supply

of electricity, not shown, the carriage and razor blade being moved parallel to the axis of the grinding wheel in the direction of the lower arrows of Figs. 1 and 2 by the cross-over dog 82 engaging in the worm-groove 47. When the dog 82 comes into contact with the inclined or cam face 49, Fig. 3, of the worm-groove, the dog 82 is caused to cross over whereby the movement of the carriage 10 and razor blade holder is reversed.

To grind the opposite side of the razor blade the razor is removed from the holder and clamped in position to reverse of that shown in Figs. 1 and 2, the operation of the machine being stopped for effecting this change.

Relative to honing the razor blade: When the dog 82 reaches the end of the worm-groove and prior to crossing over therein by contact with the face 49 for reversing the movement of said carriage, the outer side of the up-standing side-piece 53 of the carriage is brought into contact with the horizontally extending pin 35 of the slidable rod 31, and the downwardly extending pin 38 of said rod is brought into contact with the adjacent side of the neck 105, of the shifting arm 104, and the shifting arm is thrown over into the position shown in outline in Fig. 3, this arm being carried past its pivotal center by the spring 110.

Prior to this movement of the arm 103 the point 109 of the shifting lever 108 is engaged in the outer end of the slot 102 of the yoke or bail 101, and the inner clutch member 90 is maintained by the shifter plate 98 in engagement with the clutch member 87 whereby the shaft 97 and honing disk 112 thereon are caused to rotate in one direction.

Upon shifting movement of the arm 103 the point 109 of the shifting lever is shifted into engagement with the inner end of the slot 102 and the shifter plate 99 moves the clutch member 93 into engagement with the clutch member 89, and the shifter plate 98 moves the clutch member 90 out of engagement with the clutch member 87 whereby the shaft 97 and honing disk 117 thereon are caused to rotate in direction reverse to their former rotation, this reverse movement being substantially synchronous or concurrent with reverse movement of the razor blade carriage and holder.

For honing, the heel of the razor is adjustably clamped in the heel clamp 133, the edge of the razor being properly applied by the operator to the honing disk 117 with reference to the direction of rotation of this disk. Through cooperation of the shaft 97, small gear wheel 113, large gear wheel 120, arm 122, slidable block 125 and heel clamp 135 the razor blade is given a toe to heel honing movement on the surface of the honing disk 117 followed by a heel to toe honing movement upon reverse reciprocation of the

heel clamp. Upon reverse rotation of the honing disk due to reverse rotation of the shaft 97, through cooperation of the slidable rod 31, pin 142, forked arm 144, gear segment 149, small gear wheel 141, and shaft 70 137, the shaft 137 is given a partial rotation and with it the heel clamp 135 whereby the razor is carried over, pivoting as it were upon its back, and the other face and edge of the razor is applied to the honing disk 75 for honing movement, these operations being repeated until the desired honing is accomplished, the honing being done substantially concurrently with the grinding of the first 80 before mentioned razor.

Having thus described my invention, it should be understood that there may be modifications thereof and variations therein without departing from the spirit of the invention or exceeding the scope of the appended claims.

What I claim and desire to protect by Letters Patent is:—

1. A machine for sharpening and honing a plurality of razors simultaneously, comprising, in combination, a reciprocating blade-holding carriage and blade grinding means; means for honing a razor including an oscillating blade holder and an oscillatory honing means; a common means for driving all of said mechanism; and an oscillating-control means for causing oscillation of said honing means to be operated from and by the blade carriage reciprocating means.

2. A machine for grinding and honing separate blades concurrently, comprising, in combination, a stationary blade-grinder wheel; a reciprocatory blade carriage having adjustable carrying means thereon mounted for operation before said grinder; a blade honing device associated with said grinder comprising an alternately rotating hone, a blade-holding holder therewith, means for reciprocating said holder over said hone, and means cooperative with and operated by the reciprocating blade-carriage, means to cause said blade holder to oscillate in synchronism with said alternating rotating hone.

3. In a razor sharpening machine, means for automatically grinding one razor and honing another concurrently, comprising, in combination with a single operating source, of an oscillating grinder blade carrier, grinding means therefor, an alternating blade honer, oscillating reciprocating blade, holding means therefor, and connecting means between said carrier and said holder to time and control the oscillations, said holder being in synchronism with the movements of said carrier and said honer.

4. In a machine for sharpening razors, the combination of, a frame; an operatively supported motor; a drive shaft supported by said frame and driven by said motor; a

- worm shaft parallel to the axis of the grind- to said slidable rod provided with a lever ing wheel; driving means cooperating be- arm engaging in the slot of said yoke for tween the drive shaft and worm shaft for retaining one of said slidable clutch members 65 rotating the worm shaft; a razor carriage in engagement with the clutch member on having means engaging the worm shaft for one end of said sleeve to provide rotation of reciprocating the carriage in a plane parallel to the worm shaft; a slidably supported vertical shaft and honing disk in one direction, said lever arm upon shifting of rod; means cooperating between said carriage and rod for providing concurrent re- the shiftable arm upon reverse reciprocation 70 ciprocating movement of the carriage and member and engaging the other slidable rod; a shaft supported parallel to the worm clutch member with the clutch member on shaft on a lower plane than the plane of the other end of said sleeve to provide worm shaft; driving means cooperating be- rotation of said vertical shaft and honing 75 between the drive shaft and said lower shaft disk in direction reverse to their former rotation for rotating the lower shaft; a shaft sup- substantially concurrently with re- ported vertically relative to said lower shaft verse reciprocation of said carriage. 80 having one end adjacent to the lower shaft 6. In a razor sharpening machine, the combination of, a reciprocatable sliding rod; a reversibly rotatable honing disk; a station- and having on its opposite end a honing disk; bevel gear means and clutch means co- 85 20 operating between said lower shaft and ver- tical shaft for rotating the vertical shaft; and shifting means cooperating between said rod and said clutch means for causing reverse rotative movement of said vertical shaft and honing disk substantially 90 concurrently with reverse movement of said carriage in its reciprocation. 25 5. In a machine for sharpening razors, the combination of, a frame; a motor; a drive shaft driven by said motor and having thereon a grinding wheel; a worm shaft parallel to the axis of the grinding wheel; means co- 95 operating between the drive shaft and worm shaft for rotating the worm shaft; a carriage reciprocatably slidable in a plane trans- versely to the grinding wheel having a razor side and a stem portion; dash-pots for re- 100 blade holder reciprocatably therewith for receiving said plungers; and a pivotally mov- holding the razor blade in operative relation to the grinding wheel during reciprocation 105 of the carriage and holder; a slidably sup- ported rod; means cooperating between said carriage and rod for providing concurrent reciprocating movement of the carriage and rod. 40 7. In a razor sharpening machine of the rod; a shaft supported parallel to the worm shaft on a lower plane than the worm shaft and driven from the drive shaft; a shaft carriage; and a razor blade holder comprising supported vertically relative to said lower shaft having on its end adjacent to the lower shaft a bevel gear and having on its oppo- 110 site end a honing disk; clutch members slidably supported on said lower shaft; a sleeve on said lower shaft between said clutch members; the base member for reciprocatable movement therewith and for movement transversely of the carriage towards or away from said grinding wheel, an end-piece pivotally supported on the base member for tilting movement, inner 115 the sleeve having on each end thereof a hand outer blade clamping members on the bevel gear meshing with the bevel gear of said end-piece and tiltable therewith for posi- 120 tioning the edge of the razor blade relative to the grinding edge of said grinding wheel, shifting the slidable clutch members into and out of engagement with the clutch members; plates for shifting the slidable clutch members into and out of engagement with the clutch members; a tilting arm secured at one end to the end-piece and yieldably supported at its opposite end on said base member, and means for having a slot therein; and a spring con- 125 trolled shiftable arm operatively connected to the tilting arm. 60 ANIELLO DE VIVO.

ANELLO DE VIVO
